UNITED STATES PATENT OFFICE

2,616,602

BOTTLE CARRIER

Fred John Middlestadt, Baltimore, Md., assignor
to Joseph B. Waller, Baltimore, Md.

Application February 23, 1950, Serial No. 145,685

4 Claims. (Cl. 224—48)

1

The present invention relates to bottle carriers and has specific reference to a collapsible bottle carrier which may be employed to transport small groups of bottles and which may be used in storing large numbers of bottles by stacking one carrier on another.

The carrier of the present invention possesses all of the advantages and is capable of performing all of the functions of the carrier disclosed in Patent No. 2,531,092. Among these are the durability, rigidity and long life of the carrier, and ease of handling so that the carriers may be stacked above one another when they are filled with bottles, as well as the special features of construction which enable the carrier to firmly embrace the bottles when lifted by the handle and to be folded or collapsed into relatively flat condition when not in use.

The principal object of the present invention is to provide a collapsible bottle carrier which is held in the open position by the force of gravity which is augmented by the weight of the bottles being carried.

Another object of this invention is to provide a collapsible bottle carrier which firmly grips the bottles being carried between two opposed panels one movable with relation to the other.

Another object of this invention is to provide a collapsible bottle carrier which has a bottom shelf pivotally attached along one of its sides to the carrier for supporting the weight of the bottles and which may be folded inwardly to enable a relatively flat folding of the carrier when empty for convenient storage in a minimum amount of space.

Still another object of this invention is to provide a collapsible bottle carrier which carries a single row of bottles and firmly engages them when the carrier is lifted by the handle.

Yet another object of this invention is to provide a collapsible bottle carrier which can carry large or small bottles in firmly gripped position in either one or two rows.

A still further object of this invention is to provide a collapsible bottle carrier of the type described for carrying two rows of bottles which has lower shelves having outwardly projecting ridges for engaging the tops of bottles so that one carrier may be stacked above another without slipping out of alignment therewith.

And yet another object of this invention is to provide a collapsible bottle carrier of the type described which is durable and yet inexpensive to manufacture in quantity because of its simple design which requires only a minimum amount of sheet metal.

2

With these and other objects and advantages in view, which will become more apparent during the course of the following description, the invention consists in the features and combinations hereinafter set forth:

In order to make the invention more fully understood, preferred embodiments thereof have been made the subject of illustration in the accompanying drawings in which:

Figure 1 is a side elevation of the carrier in fully extended position with a load of bottles;

Figure 2 is a top plan view of the carrier with the handle partly cut away to show the fixed panel engaging the bottles being carried;

Figure 3 is an end view of the carrier in fully collapsed position, as for storage or transportation in unloaded condition;

Figure 4 is an end view of the carrier showing how the inner panel and the side panel move in vertical and converging relation when the handle is raised;

Figure 5 is a cross section showing the carrier being supported from its bottom; and

Figure 6 is an end view of the carrier of this invention which is adapted to carry and support two rows of bottles.

In its broadest concept the present invention embodies a collapsible bottle carrier constructed of rigid sheet material and which has a handle, a fixed panel, a movable panel, end members connecting the fixed panel and the movable panel for relative vertical movement, a shelf pivotally attached to the movable panel and forming a bottom for the carrier, and means limiting movement of the shelf below the horizontal plane.

By inserting bottles in the carrier and lifting the handle gravity will pull the movable panel down and inward toward the fixed panel to grip the bottles. When the carrier is empty, the shelf forming the bottom of the carrier may be folded up inside the carrier, and the carrier can then be crushed into a relatively flat condition for storage.

It is further contemplated that means be provided for carrying two opposed rows of bottles, that means be provided for conveniently stacking the loaded carriers on top of one another, and that means be provided for reinforcing the rigid material to give it greater durability.

Referring in particular to the drawings Figures 1 and 2 show the bottle carrier of this invention, generally designated as 10, which is preferably constructed of rigid sheet metal. The carrier is constructed around a handle 11 having a U-shaped cross-section for lightness. The handle includes a top portion 12 and vertical

handle members 13. A movable side panel 14 contacts bottles being carried (as shown by dotted lines) along one side thereof. A fixed panel 15 contacts the same bottles along the other side. Inwardly bent end flanges 16 are extended below the bottom edge of the panel 14 as shown at 17. End members 18 pivotally connect the panel 14 with the handle members 13. These end members 18 are attached to the panel 14 by rivets 19 which pass through the flanges 16. These members 18 are designed to give at least line contact with the bottles in each end of the carrier rather than merely contacting at one point. As shown, because of the width of members 18, they give contact with the end bottles along a vertical line for a substantial distance. The other end of the members 18 are pivotally attached to the handle members 13 by rivets 20. A bottom shelf 21 having an upwardly extending longitudinal section or flange 22 and end flanges 23 is pivoted to the flanges 16 by rivets 24.

Figure 3 shows longitudinal lip 25 which extends along the upper edge of panel 14 to give added strength to the thin sheet of metal. Also, a ridge 26 is pressed in the panel 14 to give similar strengthening characteristics. Note that the lip and ridge project outwardly, so that bottles pressed against the inside of the panel 14 will press against a flat surface rather than narrow edges. A similar strengthening lip 27 runs along the inner edge of the shelf 21. Longitudinal ridges 28 and transverse ridges 29 in the shelf 21 give added strength to the shelf. They also serve another purpose to be brought out later in connection with a double-row bottle carrier.

As shown in Figure 5 the inner or fixed panel 15 has a flange 30 through which rivets 20 pass to secure the panel to the handle member 13. An inwardly projecting lip 31 serves to strengthen this panel. Horizontal cut-outs are made in this lip at intervals at 32 as shown in Figure 2 to receive the bottles being carried so that the latter will press against the vertical surface of the panel rather than just the edge of the lip.

In operation the carrier is placed on a flat surface as shown in Figures 1 and 5 and a row of bottles are inserted therein. When the handle is initially lifted as in Figure 4 in order to transport the carrier and the bottles, the outer panel and the bottom shelf remain stationary and the handle and its inner panel due to the pivotal action of the end members move vertically and at the same time move to narrow the gap between the inner and outer panel. Therefore the bottles positioned in the carrier are gripped between the inner and outer panels in tight engagement so that they cannot fall out even if the carrier is swung back and forth or tilted to a substantial degree.

It will be noted that the bottom shelf will remain flat against the bottom surface of the bottles even when the carrier is lifted into the air because the flange 22 contacts the outer edge of the flange 16 as the shelf tends to pivot about the pivot 24 to prevent further downward movement of the shelf below the horizontal plane. It will also be readily apparent that the bottom shelf is self draining since there is a gap left between the ends of the flanges 23 and the flange 22 and the lip 27.

In order to collapse the present carrier to the position shown in Figure 3, the free end of the bottom shelf of the carrier as shown in Figure 4 is pushed upwardly toward the inside of the panel

14 as far as it will go, and then the panel and bottom shelf together are pushed down away from the handle as far as they will go. The carrier thus conforms to a relatively flat structure which may be easily stored and handled in large numbers.

Figure 6 shows a carrier embodying the principles of the present invention, which is adapted to carry two rows of bottles. On this construction the elements which are movable with respect to the handle in the single row carrier are duplicated on the other side of the handle. Since the inner panel is retained in the double row carrier the locking or gripping principle is identical with that in the single row carrier. Thus whether the carrier has one or six bottles placed in it no bottle will fall. As a matter of fact so long as bottles of the same dimension are carried in a single row of the carrier of this invention different size bottles may be carried and firmly gripped. For smaller bottles the shelf and side panel merely fall lower before the gripping action takes effect.

It should be noted that the handle has been extended in Figure 6 so that the end members are horizontal when the carrier is opened on a flat surface. In this construction the bottles of the largest size which can be carried can be loaded more quickly without having to lift the handles slightly before positioning the bottles against the bottom shelf. That is because the fixed and movable panels are furthest apart when the end members are horizontal.

The outwardly projecting ridges in the bottom shelf serve another purpose in addition to strengthening the shelf. These ridges are spaced so that when a carrier is stacked over bottles carried by a carrier below, it cannot slide over the tops of those bottles. The longitudinal ridges are spaced apart approximately the normal diameter of a bottle top to prevent transverse movement, and transverse ridges prevent longitudinal movement of the carrier.

While this invention has been described with reference to particular embodiments, it is contemplated that modifications thereof may be made without departing from the spirit of the invention. Accordingly it is intended that the scope of the invention be limited only as defined in the appended claims.

I claim:

1. A collapsible bottle carrier comprising a handle having a top portion and vertical spaced side members, a movable panel, vertically spaced end bars pivotally connected to the handle member and the movable panel at each end of the carrier, a fixed panel extending between the two handle members in order that at least one bottle may be placed between said panels to be gripped there-between when the handle is lifted, and a bottom shelf supported at one side only by pivotal connection to the movable panel and having an upwardly bent section along the one side which contacts the side panel on its outer surface to limit the downward movement of the shelf below the horizontal plane.

2. A collapsible bottle carrier comprising a handle having a top portion and vertical spaced side members, a movable panel having a vertical flanged portion at each end thereof which extends below the lower edge of the panel, vertically spaced end bars pivotally connected to the handle member and the movable panel at each end of the carrier, a fixed panel extending between the two handle members, and a bottom

shelf supported at one side by pivotal connection to the lower extension of the flanged portions and having an upwardly bent section along the one side which contacts the outer edge of the flanged portions to limit the downward movement of the shelf below the horizontal plane so that the carrier may be collapsed by folding the bottom shelf inwardly adjacent the side panel and then lowering the side panel and said shelf together to a position below and aligned with the handle.

3. A collapsible bottle carrier comprising a handle having a top portion and vertical spaced side members, a panel extending between the side members, a movable panel having flanged portions at each end thereof, vertically spaced end members pivotally connecting the handle and the flanged portion at each end of the movable panel for relative vertical movement, and a bottom shelf having a flange at each end thereof and supported at one side by pivotal connection to the flanged portions on the movable panel and having an upwardly bent section along the one side which contacts the flanged portions on the movable panel to limit the downward movement of the bottom shelf below the horizontal plane.

4. A collapsible bottle carrier comprising a

handle having a top portion and vertical spaced side members, a fixed panel extending between the two side members, a pair of opposed side panels, vertically spaced end members pivotally connecting the handle and the side panels for relative vertical movement and a bottom shelf pivotally connected at one side to one side panel, and another bottom shelf similarly connected to the other side panel, each of said shelves having an upwardly bent section along the one side which contacts the side panel on the latter's outer surface to limit the downward movement of each shelf below the horizontal plane.
